(57) **CLAIM**

The ornamental design for a front side cowl for a motorcycle, as shown and described.

DESCRIPTION

FIG. 1 is a perspective view from the front side of a front side cowl for a motorcycle.

FIG. 2 is a perspective view from the front side thereof.

FIG. 3 is a perspective view from the rear side thereof.

FIG. 4 is a perspective view from the rear side thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a right side elevation view thereof.

FIG. 10 is a left side elevation view thereof; and,

FIG. 11 is a referential view showing use thereof.

The outermost broken lines of the circular feature at the bottom right of the front side cowl for a motorcycle FIGS. 1, 2, 4, 5, 6, 9 and 11 are boundary lines and form no part of the claimed design. The other broken lines showing portions of the front side cowl for a motorcycle are for the purpose of showing environmental structure only and form no part of the claimed design.
